EDWIN H. ARNOLD, OF COVENTRY, AND WILLIAM T. WAKEFORD, OF PROVIDENCE, RHODE ISLAND, ASSIGNORS TO THE NITROGEN CORPORATION, OF PROVIDENCE, RHODE ISLAND, A CORPORATION OF RHODE ISLAND.

AMMONIA SYNTHESIS AUTOCLAVE.

Application filed November 9, 1921. Serial No. 514,088.

To all whom it may concern:

Be it known that we, EDWIN H. ARNOLD and WILLIAM T. WAKEFORD, citizens of the United States, residing at Coventry and

5 Providence, in the counties of Kent and Providence, respectively, and State of Rhode Island, have invented certain new and useful Improvements in Ammonia Synthesis Autoclaves, of which the following is a specification.

This invention relates to an improved ammonia synthesis autoclave and more particularly to certain improvements therein whereby the manipulation of the same for 15 the removal and insertion of the charge may be facilitated with consequent saving of time and labor, and increased efficiency obtained by preventing leakage under high pressures and temperatures.

20 One object of the invention is to provide a device of this character having an improved form of closure whereby the same may be readily opened or closed without undue loss of time and at the same time provide a 25 closure which will prevent the escape of the gases and not become warped or distorted under the conditions of temperature and pressure required in devices of this character.

30 Another object of the invention is to provide a device of this character which will lend itself readily to the operations of removing the spent charge and replacing the same with another without the expenditure 35 of unnecessary time and labor.

Another object of the invention is to provide a device of this character which is so constructed and arranged as to withstand high temperatures and pressures without 40 danger of leakage and wherein the several parts are so connected together and arranged relative to each other as to combine high efficiency of operation with simplicity of construction whereby the danger of explosions or injury to the apparatus or the attendants will be reduced to a minimum.

Other objects and advantages of the in-

vention relate to certain improved details of construction and modes of operation as will be more fully set forth in the detailed description to follow.

Referring to the drawings:

Fig. 1 is a perspective view of the autoclave in its operating position, the insulation container surrounding the same being shown in section to better illustrate the autoclave and its associated parts.

Fig. 2 is an enlarged vertical sectional view taken through the upper reduced end of the autoclave showing the construction of the closure.

Fig. 3 is an enlarged detail sectional view of the pressure plate and open end of the autoclave showing the manner of positioning the parts relative to each other and the packing interposed therebetween.

Fig. 4 is a vertical sectional view of the upper end of the autoclave showing a slightly modified form of the invention, and,

Fig. 5 is a top plan view of the structure shown in Fig. 4.

In the embodiment of the invention illustrated herewith 1. designates a container which may be rectangular or of any other suitable shape within which is enclosed the autoclave 2 surrounded by suitable insulating material 3, such as kieselguhr, whereby the temperature of the autoclave may be suitably maintained without undue loss by reason of radiation.

80 The autoclave 2 is provided with an elongated body portion 4 and upper and lower reduced end portions 5 and 6 respectively.

An inlet pipe 7 enters the autoclave adjacent to the upper portion thereof and extends to a point near the lower end thereof, while an outlet pipe 8 enters the autoclave and terminates near the upper portion thereof.

85 The pipes 7 and 8 are preferably welded into the steel casing of the autoclave at the points where they pass through the wall thereof to prevent any possibility of leakage around the pipes. A tube 9, having a

- closed lower end 10, is also inserted through the wall of the autoclave, being preferably welded thereto at its point of entry, and extends to a point near the lower end of the autoclave. The tube 9 serves as a container for an electric pyrometer 11 of standard construction from which extend connecting wires 12 and 13 for registering the temperature of the interior of the autoclave.
- 10 The autoclave is located in substantially upright position as shown in Fig. 1 of the drawings, and the reduced ends are provided with openings for the removal and insertion of the charges, each of these ends being
- 15 provided with closures of a character adapted to withstand high temperatures and pressures without danger of leakage while at the same time being so constructed as to permit the ready removal and replacement of the
- 20 closures when it becomes necessary to remove the spent charge and replace the same with another. The form and arrangement of the openings in the ends of the autoclave and the closure elements for closing the same
- 25 are similar at both ends of the autoclave and one of these is shown in detail in Fig. 2 of the drawings.
- The reduced open end 5 of the autoclave is provided with an exterior threaded portion
- 30 15 upon which is threaded a cupshaped cap 16, within the base portion of which is threaded a pressure screw 17 of fairly large dimensions relative to the size of the opening in the end of the autoclave. The screw
- 35 17 is provided with an angular head 18 whereby the same may be rotated in the cap 16 and the pressure screw is so positioned that its axis corresponds substantially with the major axis of the autoclave. A pressure
- 40 plate 19 fits over the open end of the autoclave within the cap 16 and is provided upon the side adjacent to the screw 17 with a seat 20 against which the end of the screw may press when forced thereagainst.
- 45 V-shaped grooves 21 and 22 are formed upon the annular face presented by the open end of the autoclave and the opposed face of the pressure plate respectively, these
- 50 grooves being of similar size and shape and arranged to register with each other when the pressure plate is positioned over the open end of the autoclave and within the cap 16. A packing ring 23 is interposed
- 55 between the annular face of the open end of the autoclave and the pressure plate 16 to fit within the registering grooves 21 and 22, and sheets of packing material 24 and 25 of asbestos, suitable metal or other appropriate material are preferably placed upon
- 60 each side of the ring 23 between the ring and the end of the autoclave and the pressure plate respectively.
- In applying the closure elements to the ends of the autoclave the ring 23 and packing strips 24 and 25 are placed over the open
- end of the autoclave and the pressure plate 19 then placed in position so that the ring and packing strips register with the grooves 21 and 22, when the cap 16 is placed in position over the open end of the autoclave enclosing the pressure plate and threaded down the desired distance. The screw 17 is then rotated to bring the end thereof into contact with the seat 20 and force the pressure plate towards the open end of the autoclave whereby the pressure plate and packing are forced firmly against the annular face of the open end and into such close engagement as to prevent leakage of gases through the closure elements.
- In Figs. 4 and 5 of the drawings is shown a slightly modified form of the invention wherein the tube 9 having a closed lower end 10 for containing the pyrometer 11 is inserted through the pressure plate 19 and the cap 16 substantially centrally thereof instead of being passed through the wall of the autoclave. In this case it is preferred to pass the tube through an opening 30 formed substantially centrally of the cap 16 to permit movement of the cap relative to the tube, while the tube 9 is welded to the pressure plate 19 where it passes therethrough. By this arrangement of the parts the tube and pressure plate are removable and replaceable as a unit while the cap may be positioned over the pressure plate and tube after the same have been placed in position. The annular face of the open end of the autoclave and the pressure plate are provided with registering grooves 21 and 22 for the reception of a packing ring 23 and packing sheets 24 and 25 as in the form previously described.
- In this form of the invention a plurality of pressure screws 31 are threaded through the base of the cap 16 and bear against the pressure plate 19 whereby the same may be forced towards the open end of the autoclave to effectively seal the same and prevent escape of the gases. Each of the pressure screws is provided with an angular head 31 by which they may be forced firmly against the upper face of the pressure plates.
- In devices of this character as heretofore employed where temperatures of from 400° to 600° C are employed and the gases being synthesized are subjected to high pressures of from 1000 to 1500 pounds per square inch great difficulty has been encountered in providing a closure for the autoclave which will withstand temperatures and pressures of the orders mentioned without becoming warped or distorted so as to make the task of removing and replacing the same extremely difficult as well as in some cases causing loss of the gases to such an extent as to make it necessary to stop operations and repair the parts. By the use of the struc-

ture shown and described herewith these difficulties have been overcome and the expenditure of time and labor in removing and replacing the closures greatly reduced as well as the danger of leakage substantially eliminated. In the use of our improved structure important economies of operation are effected by the provision of the novel closures and the arrangement of the parts. It has heretofore been the practice to use an autoclave provided with a single opening positioned at the top thereof and in removing a charge it was therefore necessary to remove the closure and force the spent material out by forcing the working gases into the autoclave under high pressures through the pipes 7 and 8. This is a long and difficult procedure but was the only practicable method so long as no approximately perfect closure mechanism could be provided for the openings in the autoclave, since to provide another opening in the autoclave would double the losses from leakage as well as increase the time and labor in removing and replacing the closures. By means of our improved construction of closure we are enabled to provide openings both at the top and at the bottom of the autoclave whereby in the removal of the spent charge the bottom closure may be removed without disturbing the top closure, and the material forced out by the combined action of gravity and gas pressure introduced through one of the pipes 7 and 8. Upon the removal of the charge the closure at the bottom of the autoclave is replaced and that at the top opened through which a fresh charge is inserted. Thus it will be seen that important advantages of operation are secured as well as a more efficient closure mechanism for devices of this character. The autoclave as well as the cap pressure plate and packing ring are preferably all formed of steel, vanadium steel alloy or other suitable alloy, the autoclave being of seamless construction to better withstand the pressures employed.

While we have shown and described in considerable detail one embodiment of our invention which we have found efficient in operation; we are aware that various modifications may be made therein without departing from the spirit of our invention, and therefore, we do not desire to be limited to the precise details of construction shown and described except as the same may properly be included within the scope of the appended claims when broadly construed.

Having described our invention, what we claim is:

60 1. An ammonia synthesis autoclave comprising an elongated body portion provided with reduced ends, inlet and outlet pipes entering said body portion and terminating at unequal distances from the base thereof, a tube provided with a closed

end projecting within said body portion, and independently removable closures for the reduced ends of said body portion.

2. An ammonia synthesis autoclave comprising an elongated body portion formed 70 of a single metallic shell surrounded by heat insulating material and having inlet and outlet pipes projecting therein for conveying gases to and from said body portion, said body portion being provided with reduced ends, and independently removable closures for said reduced ends.

3. An ammonia synthesis autoclave comprising a body portion provided with a reduced open end, a cap threaded upon the 80 reduced end of the autoclave and provided with a threaded opening, a closure plate fitting over the open end of the autoclave and within the cap, and a pressure screw threaded within the threaded opening in 85 the cap and bearing against one side of the pressure plate to hold the same firmly in contact with the open end of the autoclave.

4. An ammonia synthesis autoclave comprising a body portion provided with a reduced open end, a closure for said open end comprising a cap threaded upon the reduced end of the autoclave, a pressure plate positioned within the cap and contacting with the open end of the reduced end of the autoclave, and adjustable means carried by the cap for exerting pressure upon the pressure plate and holding the same firmly against the open end of the 100 autoclave.

5. An ammonia synthesis autoclave comprising a seamless body portion provided with a reduced end, and a closure therefor comprising a pressure plate, a cap enclosing said plate and engaging the reduced end of said autoclave, and a means carried by said cap and adjustable relative thereto for forcing said plate into close engagement with said reduced end and 110 holding the same in position under pressure.

6. In an ammonia synthesis autoclave comprising a body portion provided with a reduced open end, a pressure plate fitting 115 over said open end, a packing ring interposed between the end of said autoclave and said plate; a member secured to said autoclave and enclosing said plate, and adjustable means carried by said member 120 for exerting pressure upon said plate to force the same towards said reduced end.

7. In an ammonia synthesis autoclave comprising a body portion provided with an open end, a pressure plate fitting over said open end the adjacent surfaces of said end and said plate being provided with cooperating grooves, a packing ring interposed between the end of the autoclave and said plate in registry with said grooves, a mem- 130

- ber secured to the autoclave and enclosing said plate, and adjustable means carried by said member for exerting pressure upon said plate to force the same towards said open end of the autoclave.
8. An ammonia synthesis autoclave comprising a body portion formed of a single metallic shell and provided with reduced ends, means for placing the interior of said autoclave under pressure, and independently removable closures for the reduced ends of said autoclave whereby the charge may be withdrawn and replaced through the closures located at opposite ends of the autoclave.
9. An ammonia synthesis autoclave comprising a body portion formed of a single metallic shell provided with oppositely located openings, means for placing the interior of said autoclave under pressure, and independently removable closures for said openings whereby the charge may be removed from said autoclave by the combined influence of gravity and pressure.
10. In an ammonia synthesis autoclave, a seamless body portion provided with an opening therein, a closure for said opening, an inlet and outlet pipe for said autoclave each opening into the interior thereof and welded to the body portion, said inlet pipe 30 terminated at a lower level than said outlet pipe, and a pyrometer enclosing tube projecting within said body portion and welded thereto.
11. An ammonia synthesis autoclave provided with an open end, a pressure plate fitting over said open end and serving as a closure therefor, a cap detachably secured to the outer surface of said autoclave adjacent to said open end, and independently adjustable means carried by said cap for forcing said pressure plate towards the end of said autoclave and holding the pressure plate securely thereagainst.
12. In an ammonia synthesis autoclave comprising a body portion provided with a reduced open end, a pressure plate fitted over said open end, a member overlying said pressure plate and secured to the end portion of said autoclave, and means carried by said member for exerting pressure upon said pressure plate to force the same towards said reduced end.

In testimony whereof we have affixed our signatures.

EDWIN H. ARNOLD.
WILLIAM T. WAKEFORD.
